SURFACE SUPPORTED FRICTION CAP REMOVER

Filed Oct. 19, 1946

UNITED STATES PATENT OFFICE

2,542,295

SURFACE SUPPORTED FRICTION CAP
REMOVER

Livingston M. Spraker, Palatine Bridge, N. Y.

Application October 19, 1946, Serial No. 704,357

3 Claims. (Cl. 81—3.3)

1

The present invention relates to devices for removing closure caps from glass jars, bottles and other containers.

The principal object of the present invention is to provide a device of this character which is simple in construction, and which is capable of easily and quickly effecting removal of closure caps without danger of bending or otherwise distorting the cap or breaking the glass jar or other container.

The invention is illustrated, by way of example, in the accompanying drawing, in which:

Figure 1 is a view in perspective of the device, in its preferred form;

Fig. 2 is a side view of the device shown attached to the underside of a shelf or other support with a glass jar, and a bottle such as a ketchup bottle, in position to effect removal of their caps, the bottle and the jar being shown by dotted lines;

Figs. 3 and 4 are sectional plan views respectively taken on the lines 3—3 and 4—4 of Fig. 2;

Fig. 5 is a view similar to Fig. 4 but showing a modified form of the device;

Fig. 6 is a bottom plan view of the same; and

Fig. 7 is a section taken on the line 7—7 of Fig. 5.

The device illustrated in Figs. 1 through 4 of the drawings may be made of a single strip of sheet metal, and has a horizontal portion 2 which is adapted to be secured by screws 4 to the underside of a shelf or other support 6, the screws passing through apertures 8 in said portion. The ends of the horizontal portions 2 are bent downwardly to provide upright portions 10 and 12. At the lower end of these portions are outwardly bent lips 14 and 16, respectively.

The end of the device having the lip 14 is particularly adapted for removing the cap 18 of a vacuum sealed glass jar 20, or other container that is provided with a shallow cap such as bottles having crown caps. The other end of the device is particularly adapted for removing the cap 22 of a ketchup bottle 24, or other container having a similar cap.

The edge of the lip 14 is curved to conform generally with the curvature of the neck of the jar 20 or other container to be opened thereby. The edge of the lip 16 is curved to conform generally with the curvature of the neck of the ketchup bottle 24 or other container to be opened thereby. The upright portions 10 and 12 may be transversely curved correspondingly to the edges of the associated lips 14 and 16. The center of the edge of the lip 14 is spaced from the upright 10 a distance slightly less than the distance from

2

the outer edge of the skirt of the cap to the adjacent portion of the neck of the container 20. The center of the edge of the lip 16 is spaced from the upright 12 a distance slightly less than the distance between the outer side of the lower edge of the cap 22 and the neck of the container 24. The lip 14 is spaced a slightly greater distance from the underside of the shelf or other support 6 than the height of the cap 18. The lip 16 is spaced a slightly greater distance from the underside of the shelf 6 than the height of the cap 22.

With this construction, to remove the cap 18 from the jar 20, the jar is positioned with the lower edge of the cap engaging the top side of the lip 14, and with the outer side of the lower edge of the skirt of the cap engaging the upright 10. When thus positioned, upon applying an upward and outward forcing movement to the lower end of the jar so as to cause the jar to be swung about the point of engagement of the top of the cap with the underside of the support 6, the cap may be easily removed from the jar.

It will be noted that during this prying off movement, the transversely curved upright 10 by being engaged by the outer side of the lower edge of the skirt of the cap serves as a guard to effectively prevent the neck of the jar, as the jar is pried from beneath the cap, from striking the lip, which in the case of glass jars would be liable to result in breaking or chipping of the glass. Also, owing to the wide area of engagement of the lip 14 with the lower edge of the cap, and the fact that the top of the cap during this movement engages the flat surface provided by the underside of the shelf, the removal of the cap may be effected without bending or otherwise distorting the cap, so that the cap may be replaced on the jar for resealing purposes. The engagement of the side of the cap with the curved upright assists the correspondingly curved lip in holding the cap and jar in proper position during the removal of the cap. Because of the ease in thus effecting removal of the cap and the minimum amount of movement of the jar required, although the jar as initially held in vertical position and during removal of the cap is tipped at an angle, the removal of the cap may be accomplished without danger of spilling the contents of the container.

It will be apparent that the cap 22 may be removed from the bottle 24 by means of the end of the device that includes the prying off lip 16 in the same manner as in the case of the removal of the cap from the glass jar 20.

The form of the device illustrated in Figs. 5

and 6 also may be made of a single strip of sheet metal. This device is provided with a horizontal portion 26 having its ends bent downwardly to provide upright portions 28 and 30 which have their inner ends bent inwardly or toward each other to provide lips 32 and 34. The lip 32 corresponds to the lip 14 of the device first described, and the lip 34 corresponds to the lip 16. The upright portions 28 and 30 may be transversely curved correspondingly to the edges of the lips 32 and 34. The device may be secured to the shelf 6 or other support by means of screws 36 that extend through apertures in the horizontal portion 26, the heads of the screws being countersunk so that their outer surfaces are flush with the underside of the horizontal portion 26.

With this construction, the cap may be removed from a jar corresponding to the jar 20, upon positioning the jar with the lower edge of the cap extending over the lip 32, and with the top of the cap engaging the underside of the horizontal portion 26. The cap may be removed from a bottle, such as the bottle 24, by means of the lip 34 in a similar manner.

In the several forms of the device, the points 37 of the lips are preferably tipped or bent slightly upward (approximately $1/32$ of an inch) to permit them to engage the turned under edge of the cap. This not only insures maximum engagement of the lip with the cap but also tends to hold the cap in engagement with the opener so as to prevent the container from slipping out of, or away from, the opener when pressure is applied. Thus the points serve to assist the curved lip and the transversely curved upright in maintaining the cap in proper engagement with the opener during the prying off operation. This feature is particularly advantageous in the case of vacuum sealed glass jars to ensure removal of the cap without danger of distorting it by bending.

As will be evident to those skilled in the art my invention permits various modifications without departing from the spirit thereof or the scope of the appended claims.

What I claim is:

1. A device for removing closure caps from jars, bottles, or the like, comprising a member adapted to be secured to the underside of a shelf or other support, having an upright portion and a laterally projecting lip at the lower end of said portion having its outer edge curved to conform generally with the curvature of the neck of the container to be opened and having its central portion spaced from said upright portion a distance less than the distance between the outer side of the lower edge of the skirt of the cap and the adjacent portion of the neck of the container, whereby the cap may be removed from the container upon positioning the container with the top of the cap engaging a flat surface spaced from the upper side of said lip a distance slightly greater than the height of the cap and with the lower edge of the skirt of the cap held against the top side of the lip, and forcing the lower portion of the container outwardly, said upright

portion by the engagement of the side of the cap therewith serving as a guard to prevent the end of the jar striking the lip as the cap is removed.

2. A device for removing closure caps from jars, bottles or the like, comprising a member having a horizontal portion adapted to be secured to the underside of a shelf or other support, an upright portion at one end of said horizontal portion, and a lateral projecting lip at the lower end of said upright portion and extending over said horizontal portion, the edge of said lip being curved to conform generally with the curvature of the neck of the container to be opened, and the central portion of said lip being spaced from said upright portion a distance less than the distance between the outer side of the lower edge of the skirt of a cap and the adjacent portion of the neck of the container, and said lip being spaced from said horizontal portion a distance slightly greater than the height of the cap, whereby the cap may be easily removed from the container upon positioning the top of the container in engagement with the underside of said flat portion of the device and with the lower edge of the cap held against the top side of the lip, and forcing the lower portion of the container outwardly, said upright portion by engagement of the side of the cap therewith serving as a guard to prevent the neck of the container striking the lip during removal of the cap.

3. A device for removing closure caps from jars, bottles, or the like, made from a single strip of metal and adapted to be secured to the underside of a shelf or other support, comprising an upright portion and a laterally projecting lip at the lower end of said portion, the edge of said lip being curved to conform generally to the curvature of the neck of the container to be opened and the ends of said lip being bent upwardly slightly whereby the cap may be removed from the container upon positioning the container with the top of the cap engaging a flat surface spaced from the upper side of said lip a distance slightly greater than the height of the cap and with the lower edge of the skirt held against the top side of the lip, and forcing the lower portion of the container outwardly, the upwardly bent ends of the lip engaging the under edge of the cap so as to assist in holding the cap in proper engagement with the opener during the prying off operation.
